Primary Examiner — Ian Simmons*Assistant Examiner* — Keith Frank(74) *Attorney, Agent, or Firm* — Lucas & Mercanti, LLP(57) **CLAIM**

The ornamental design for a jug, as shown and described.

DESCRIPTION

FIG. 1 is a left side elevation view of a jug showing our new design;

FIG. 2 is a front elevation view thereof;

FIG. 3 is a rear elevation view thereof;

FIG. 4 is a right side elevation view thereof;

FIG. 5 is a top plan view thereof;

FIG. 6 is a bottom plan view thereof; and,

FIG. 7 is a perspective view thereof.

The broken lines in the drawings showing the jug illustrate the portions of the jug that form no part of the claimed design.
